[57] **CLAIM**

The ornamental design for a multi-purpose flash light,
as shown and described.

DESCRIPTION

FIG. 1 is a front-right-top perspective view of a multi-purpose flash light, showing my new design;

FIG. 2 is a front elevational view thereof;

FIG. 3 is a rear elevational view thereof;

FIG. 4 is a right elevational view thereof, a left elevational view being a mirror image thereof;

FIG. 5 is a top plan view thereof;

FIG. 6 is a bottom plan view thereof; and,

FIG. 7 is a front-right-top perspective view thereof,
with the broken line showing for illustrative purposes
only and forming no part of the claimed design.

FIG.1

FIG.7

FIG. 3

FIG. 2

FIG. 4

FIG. 6

FIG. 5
